UNITED STATES PATENT OFFICE.

LUTHER STIERINGER, OF NEW YORK, N. Y., ASSIGNOR TO THE EDISON
LAMP COMPANY, OF HARRISON, NEW JERSEY.

INCANDESCING ELECTRIC LAMP.

SPECIFICATION forming part of Letters Patent No. 341,778, dated May 11, 1886.

Application filed January 13, 1886. Serial No. 188,446. (No model.)

To all whom it may concern:

Be it known that I, LUTHER STIERINGER, of New York city, in the county and State of New York, have invented a certain new and

5 useful Improvement in Incandescing Electric Lamps, of which the following is a specification.

Heretofore when incandescing electric lamps have been used in series with currents of high 10 electro-motive force, with an electro-magnetic cut-out device for closing a shunt around each lamp, when its carbon filament breaks difficulty has arisen in the following way: If a break occurs in the filament, the current is apt 15 to pass from the broken side of the filament below the point of fracture across the vacuous space to the other side, forming an arc which follows down the carbon, consuming the same, and down the leading-in wires to the glass, 20 which being intensely heated becomes a conductor of electricity, so that the current continues to pass through the glass from one wire to the other and so proceeds down to the lamp-socket and cut-out mechanism so that these 25 parts may be destroyed and the continuity of the series-circuit is finally broken. The passage across the carbon being provided for the current as soon as the carbon breaks the cut-out mechanism of course does not act.

30 My invention relates to means for overcoming this difficulty by breaking the arc before it leaves the lamp, so that the electro-magnetic cut-out will then act to shunt the lamp. I accomplish this by filling the stem or tube 35 through which the leading-in wires pass outside of the exhausted globe with a refractory insulating material which is not injuriously affected by the heat of the arc or current and prevents the arc from passing from the wire 40 to the glass, or from one wire to the other. The substance which I have found best to employ for the purpose is asbestos fiber, with which I fill the stem or tube. I have, however, tried numerous other substances with 45 good results. Among these I may mention magnesium calcite, powdered soapstone, and terra-alba. These substances are effective in operation, but the asbestos fiber is easier to handle and does not shift its position like the 50 other materials, which are in the form of powder. Any refractory insulating material not

unduly affected by the arc may, however, be employed, and such materials I consider the equivalents of asbestos fiber for the purposes of my invention.

55 When lamps such as just described are used in series, I provide each with a suitable electro-magnetic cut-out device. If, when the carbon breaks, the arc is not formed—which often occurs—the cut-out device acts at once to shunt 60 the lamp and maintain circuit to the rest of the series; and when the arc does occur and is broken in the stem of the lamp the cut-out mechanism acts also in the same way.

65 My invention is illustrated in the annexed drawings, in which Figure 1 is a diagram of a portion of a system of electric lighting embodying my invention; Fig. 2, a view in elevation of one of the lamps, and Fig. 3 a section of the stem of the lamp after the arc has been formed 70 and broken.

75 Like letters refer to corresponding parts in all these figures.

A is the exhausted inclosing-globe of an Edison electric lamp.

75 B is the inner tube or stem through which the leading-in wires *a a'* pass, being sealed in the glass of said tube where they pass through it at *b*.

80 C is the carbon filament, attached to said wires at *cc'*, preferably by electro-plated joint. When the arc forms across the filament, it usually passes from the broken side thereof immediately below the fracture to the opposite clamps. Both sides of the filament are consumed at once and the wires usually are then 85 consumed down to the glass, or nearly there. The current then passes across through the glass and usually consumes only one wire, *a*, as seen in Fig. 3. Continuing on through the 90 wires and glass the current continues to prevent the operation of the cut-out, and finally reaches and destroys the socket and cut-out mechanism. I however, as explained, fill the stem B with asbestos fiber D or other suitable 95 material. The stopper E, inserted in the lower end of the stem, holds the asbestos in it and also keeps the wires apart. At first, as seen in Fig. 3, the wire continues to be consumed for a certain distance down into the asbestos— 100 that is, until the distance becomes so great that the current or arc cannot pass from the end of

the wire to the glass at *b*. As soon as this point is reached, it is evident that the arc must cease at once since the asbestos prevents it from reaching the other wire direct or from reaching the side of the tube.

5 In Fig. 1 is shown a cut-out device which may be employed.

The lamps *A A* are in series in line *L L* in any suitable number. In a shunt, *d d*, around 10 each lamp is an electro-magnet, *F*, whose spring-retracted armature-lever *G* controls at *e* another shunt, *f f*. If circuit through the lamp is interrupted in either of the two ways above described, the magnet *F* attracts its armature and closes shunt *f f* around the lamp. 15 A catch, *g*, is provided which holds the shunt closed until the broken lamp is replaced by a new one, when the catch is withdrawn by hand and the shunt is opened again.

20 I am aware of United States Patent to Perkins, No. 287,314, dated October 23, 1883, in which is described the use of mineral wool placed in the stem of a lamp to prevent the conduction of heat down to the socket. Mineral wool is, however, not a material which is 25 refractory under the heat of the arc, and will not act to break the arc in the manner above set forth.

What I claim is—

1. In an incandescent electric lamp, the 30 leading-in wires within the stem of the lamp separated from each other and from the glass of the stem by asbestos fiber or equivalent refractory insulating material, substantially as set forth.

35 2. In an incandescent electric lamp, the glass stem through which the leading-in wires pass filled with asbestos fiber or equivalent refractory insulating material, substantially as set forth.

40 3. The combination, with two or more incandescent electric lamps connected in series, each having its leading-in wires within the glass stem separated from each other and from the glass by asbestos fiber or equivalent refractory insulating material, of electro-magnetic cut-out mechanism for each lamp, substantially as set forth.

45 This specification signed and witnessed this 4th day of January, 1886.

LUTHER STIERINGER.
